(57) **CLAIM**

The ornamental design for a notebook computer, as shown and described.

DESCRIPTION

FIG. 1 is a front perspective view of a notebook computer showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is another perspective view in which the notebook computer is shown in a closed position.

FIG. 9 is an exploded view of the notebook computer in which the keyboard is shown outside of the notebook computer; and, FIG. 10 is another right-side view of the notebook computer in which the notebook computer is shown in a fully extended position.

The broken lines are for environmental purposes only and form no part of the claimed design.
